UNITED STATES PATENT OFFICE.

BERNARD D. WILLIS, OF OAK PARK, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed December 3, 1919. Serial No. 342,239.

To all whom it may concern:

Be it known that I, BERNARD D. WILLIS, a citizen of the United States of America, and a resident of Oak Park, in the county of Cook 5 and State of Illinois, have invented certain new and useful Improvements in Automatic Telephone Systems, of which the following is a specification.

My invention relates in general to automatic telephone systems, and has for its object the provision of means for limiting the time during which a subscriber can hold a trunk for his own exclusive use. In the operation of the system herein contemplated, 10 when a trunk line is taken for use by a calling subscriber, the trunk is made busy and the use thereof is made exclusive for a certain definite time, after which the subscriber is given a signal and the busy condition is removed, whereby the trunk line is rendered accessible to other calling subscribers. Then if no other subscriber should attempt to take the trunk line, the subscriber first calling 15 may still continue to use it as long as he desires, even though it is nonbusy; but as soon as a second calling subscriber extends a connection thereto, the connection of the first calling subscriber is released.

While my invention is applicable to any or 20 all of the trunk lines in the well known trunking systems, it is particularly valuable in certain special cases, as where, for example, a certain group of trunk lines is inadequate to handle the traffic, and it becomes necessary 25 to adopt some means of limiting the unrestricted use thereof. The adaptation of the invention to a situation of this kind will be described hereinafter, reference being had to the accompanying drawings, in which Figs. 30 1 and 2 are circuit diagrams, while Fig. 3 is a diagrammatic layout of a system embodying the invention.

Referring to Fig. 3, consider two exchanges, a main exchange and a branch exchange. The main exchange is an automatic exchange in which connections are established through the medium of automatic switches under the control of calling subscribers. Suppose, for example, that the subscriber at 35 substation A desires to call the subscribers at substation A'. The connection is established by means of the individual line switch C', a first selector such as the first selector D, a second selector such as the second selector

E, and a connector such as the connector H. 55 This is the usual and well known percentage trunking system. At the branch exchange connections may be established manually by operators through the medium of cord circuits. To handle connections between the 60 branch exchange and the main exchange a group of two way trunk lines is provided, one of which is indicated by reference character X. These trunk lines terminate in jacks at the manual branch exchange and at the main 65 exchange are each provided with two branches one of which terminates in an individual line switch, while the other is multiplied in the banks of a group of so called ringing selectors. Considering first calls 70 from the branch exchange to the main exchange, the substation A² may be connected with substation A as follows: jack J², cord circuit O, jack J', trunk line X, individual switch C², first selector D, second selector E, 75 and a connector H. The ringing selectors mentioned above are provided to handle calls in the other direction, and may be accessible from a certain level in a certain group of second selectors. A connection from substation A' to substation A² may then be extended by way of the individual switch C, the first selector D, second selector E, ringing selector F, trunk line X, jack J', cord circuit O, and jack P². 80

With the above general layout in mind it will be assumed that for some sufficient reason it is considered necessary to limit the holding time on the trunk lines when they are used for main branch calls. The specific means for accomplishing this is applied to the ringing selectors and its operation will now be described. In view of the well known character of the equipment used only sufficient of the circuits have been shown to 85 enable the invention to be understood; and reference is made to the following patents as showing the state of the art; U. S. Patent to Keith, Erickson and Erickson, No. 815,321. U. S. Patent to Keith, Erickson 90 and Erickson, No. 815,176. U. S. Patent to Lamb, No. 1,193,160. U. S. Patent to Powell, No. 1,308,553. United States Patent to Erickson, No. 1,330,019.

For the purposes of this explanation it 105 will be assumed that the subscriber at substation A has extended a connection through the medium of his individual line switch

- and a first and second selector to the ringing selector F, Fig. 1, the wipers of the second selector in use having established connection with the bank contacts 2, 3 and 4. 5 The conductors of the calling line are thus extended by way of bank contacts 2 and 3, trunk conductors 5 and 7, and normally closed contacts of the reversing relay 8 to the windings of the double wound line relay 9, which is thereupon energized to complete a circuit for the slow acting release relay 12. Upon energizing, relay 12 prepares the usual circuit for the vertical magnet 20 at its armature 37, and at its armature 15 38 connects ground G' to the release trunk conductors 6, thereby completing the usual holding circuit for maintaining the selector switches and the line switch in operated position. 20 The selector F is now ready to respond to impulses. The calling subscriber will therefore operate his calling device and dial in accordance with the last digit in the number assigned to the branch exchange trunks 25 with the result that a series of interruptions is produced in the circuit of the line relay 9. The line relay deenergizes a corresponding number of times and at each deenergization sends a current impulse through the 30 slow acting series relay 12 and the vertical magnet 20 to battery. By the operation of the vertical magnet the switch shaft is raised step by step until the wipers 21-23, inclusive, stand opposite the bank level in which 35 are located the terminals of the lines extending to the branch exchange. The slow acting relay 13 is energized in series with the vertical magnet, maintaining its armature 39 attracted throughout the vertical movement of the switch, and at the first upward 40 movement of the shaft completes a circuit which extends by way of the working contact of the said armature, the off-normal springs 52, and the winding of the stepping relay 14 to battery. The stepping relay 14 is energized, prepares a circuit for the rotary magnet 19 at its armature 41, and at its armature 40 locks itself to the grounded 45 release trunk conductor 6. 50 At the end of the vertical movement of the switch the slow acting relay 13 is deenergized, and at the resting contact of armature 39 completes the circuit of the rotary magnet 19, thereby initiating the operation of selecting an idle trunk line. Upon 55 energizing, the rotary magnet advances the wipers 21-23, inclusive, into connection with the first set of contacts in the level opposite which they were raised, and at the same 60 time interrupts the locking circuit of the stepping relay 14 which thereupon deenergizes and breaks the circuit of the rotary magnet which in its turn deenergizes. The 65 operation now depends upon whether the test wiper 22 is in engagement with a grounded or nongrounded test contact. If the trunk line terminating in the first set of contacts is busy the test contact associated therewith will be grounded and a circuit will be completed which extends from the 70 grounded test contact by way of the test wiper 22, armature 46 and its resting contact, left hand interrupter contact of magnet 19, off normal springs 52, and the winding of the stepping relay 14 to battery. The stepping relay is therefore again energized with the result that the rotary magnet 19 is also energized again to advance the switch wipers into engagement with the next 75 set of bank contacts. This operation will 80 continue as long as the test wiper 22 continues to engage grounded or busy test contacts. As soon as a nongrounded test contact is reached, which we will assume to be the test contact 25 associated with the trunk line X, the stepping relay 14 will not again 85 be energized, but the switching relay 16 which heretofore has been short circuited, will be operated by current flow in the following circuit: grounded release trunk conductor 6, contacts controlled by armature 27 of relay 8, conductor 6', winding of the switching relay 16, left hand interrupter contact of magnet 19, off normal springs 52, and the winding of the stepping relay 14 to 90 battery. The resistance of the switching relay 16 is so high that the stepping relay 14 is not operated. Upon energizing, relay 16 opens the circuit of the vertical magnet 95 at its armature 48, completes a circuit for the wiper switching relay 17 at its armature 47, and at its armature 46 completes a circuit over the test wiper 22 as follows: 100 grounded release trunk conductor 6, contact springs controlled by armature 27, conductor 6', contact springs controlled by armature 35, working contact of armature 46 and the said armature, test wiper 22, test contact 25, winding of the switching relay 100 of the line switch C² and the winding 105 of the stepping magnet of the said line switch to battery. By the closure of the above circuit ground potential is placed 110 upon the test contact 25 and its multiples, the trunk line X is made busy to other calling subscribers, and also the switching relay 100 in the line switch C² is energized to disconnect the trunk conductors from their 115 normally closed connections in the said line switch. The relay 100 operates slightly before the relay 17 in the selector, the latter relay being made somewhat slow to energize by means of a copper slug. Upon the 120 operation of the latter relay the line wipers 21 and 23 are connected at armatures 49 and 50, respectively, and a signalling circuit is 125 thereby established whereby ringing current from the generator Gen is projected out over the trunk line to operate the bridged relay 105 at the branch exchange. 130

The circuit extends by way of the resting contact of armature 45 and the said armature, armature 50 and its working contact, wiper 23, bank contact 26, line conductor 102, contacts of key K, the condenser and upper winding of relay 105, upper contacts of relay 104, contacts of key K, line conductor 101, bank contact 24, line wiper 21, working contact of armature 49 and the 5 said armature, armature 44 and its resting contact, and the upper winding of relay 15 to battery. The relay 15 does not respond to ringing current in the above circuit, but the relay 105 is operated, completes a locking circuit for itself, and closes the circuit of the lamp L' which is lighted to signal the operator.

The connection has now been extended to the branch exchange and a signal has been 10 actuated at the operator's position. When the operator observes the lighted lamp she will answer by inserting the left hand plug of her cord circuit O in the jack J' at the same time throwing her key K² to listening 15 position. By the insertion of the plug in the jack the polarized relay 107, which is in series with the left hand winding of the repeating coil in the cord circuit, is bridged across the trunk conductors 101 and 102. 20 As a result relay 15 at the ringing selector is energized, either by current from the generator Gen or by direct current from the battery associated therewith, thereby establishing a locking circuit for itself at its armature 43, and at armatures 44 and 45 closing the trunk conductors 5 and 7 through to the line wipers 21 and 23, respectively. The 25 double wound relay 8 is now connected in bridge of the trunk line and is energized by current flow thereover. At armatures 28 and 29 relay 8 reverses the direction of current flow in the calling line in the usual manner, at armature 30 a circuit is completed for the magnet 75 of the time mechanism, and at armature 27 the release trunk conductor 6 is disconnected from conductor 6', and the latter conductor is connected to ground by way of armature 27, armature 42 and its working contact, and off normal 30 springs 53 and 54 to ground.

At the branch exchange, the operator may now obtain the desired number from the calling subscriber which in this case is the number of the subscriber at substation A², and 35 will then complete the connection by inserting the right hand plug of the cord circuit O in the jack J², after which the key K² will be thrown to ringing position for a moment. By this operation the cut-off relay associated with the line of substation A² is energized in series with the sleeve relay 109 of the cord circuit, which latter relay causes the illumination of the supervisory lamp L². Although the relay 106 at the 40 other end of the cord circuit is also energized over the sleeve of the cord the supervisory lamp L² is not lighted because of the fact that the polarized relay 107 is energized in the proper direction to open its circuit. When the called subscriber answers 70 the double wound relay 108 will be operated and the lamp L² will be extinguished.

The connection has now been established and the subscribers can converse as desired. In accordance with the invention, however, the time during which the calling subscriber can retain the trunk line for his own exclusive use is limited and the operation of the time mechanism will now be considered. As stated before, when relay 8 at the selector 75 is energized a circuit is completed for the magnet 75 of the time mechanism. This mechanism is described fully in one of the publications previously referred to and will not be explained in detail herein. 80 It will be sufficient to say that when the magnet 75 is energized the roller 77 which is constantly rotating in a counter clockwise direction begins to raise the plunger 76. After a predetermined time which may be, for example, five minutes, the contact springs 78 and 79 are closed, thereby completing a circuit for the lower winding of relay 11. Upon energizing, relay 11 disconnects the 85 test wiper 22 from the conductors 6' and completes a locking circuit for its upper winding as follows: ground at G⁷, upper winding of relay 11, armature 35 and its working contact, working contact of armature 46 and the said armature, test wiper 22, test contact 25, winding of relay 100, and the winding of the stepping magnet of line switch C² to battery. The upper winding 90 of relay 11 is of high resistance, not so high of course that the relay 100 will deenergize, but sufficiently high to reduce the ground potential on the test contact 25 to a point where the trunk line is made non-busy. At its lower armature 36 relay 11 95 breaks the circuit of the magnet 75 of the time mechanism, thereby permitting the plunger 76 to restore, and at the same time removes the short circuit from the lower winding of relay 10, thereby causing this 100 relay to energize in series with the line relay 9. Upon attracting its armature 32 relay 10 includes its upper winding in the circuit and at its armature 33 prepares a circuit for the release magnet 18. Also 105 at armature 34 ground is disconnected from the original energizing circuit of the wiper switch relay 17, but this relay remains energized by reason of the alternative ground connection at armature 36 of relay 11. At 110 the same time that contact springs 78 and 79 were closed the contact springs 80 and 82 will be closed also. By this operation a circuit is closed for the secondary of the repeating coil forming part of the signalling 115 mechanism Q. The circuit may readily be 120 125 130

traced from ground through the condenser in the said secondary winding, contact springs 81, 82 and 80, also lower winding of relay 9 and the lower winding of relay 5 10 to ground. An audible tone is thus placed on the calling line which notifies the calling subscriber that the period of exclusive use has terminated and that he is liable to be disconnected at any time. The signal endures for only an instant; however, and the conversation may continue as long as desired subject only to the possibility of release by a second calling subscriber who may attempt to establish connection with the 15 trunk line in use. If we assume that the conversation proceed without interruption until it is finished both subscribers will replace their receivers. Disconnection is accomplished in the usual manner which may 20 be briefly explained as follows: By the replacement of the receiver at the calling station the line relay 9 of the selector F is deenergized, thereby causing the deenergization of the release relay 12 which in turn 25 deenergizes to close the circuit of the release magnet 18 whose function it is to restore the selector to normal position. Relay 12 also disconnects ground from the release trunk conductor 6, whereby the individual 30 line switch of the calling subscriber and the selector switches in use are also restored to normal. When the selector F is restored to normal the circuit of the switching relay 100 of the line switch C² is broken thereby 35 restoring the normal connections in the line switch with the result that it is operated in the usual manner to extend a connection to an idle first selector. The direction of current flow over the trunk line is now reversed 40 and the polarized relay 107 at the cord circuit O is operated in such a manner that it will close the circuit of the supervisory lamp L². The replacement of the receiver at substation A² breaks the circuit of the 45 relay 108 which therefore deenergizes to close the circuit of the supervisory lamp L³. The disconnect signals thus displayed indicate to the operator that the conversation is finished and she will pull down the connection.

We will assume now that a second calling subscriber attempts to establish connection with the trunk line X before the conversation just described is finished. It has been 55 previously stated that the trunk line is made nonbusy after a predetermined time by the substitution of ground through the upper high resistance winding of relay 11 for direct ground. Then the relay, corresponding 60 to relay 14, of the second selector which is being used by the second calling subscriber will not energize when the wipers of the selector make connection with the trunk line, the rotation of the selector will cease and connection with the trunk line will be established

as is usual in the case of idle trunk lines. Following the establishment of the connection, direct ground will be placed upon the multiple of test contact 25 in the bank of the other selector and the upper winding of relay 11 70 will be short circuited. Relay 11 therefore is deenergized and a circuit is completed for the release magnet 18 as follows: ground at G⁸, armature 36 and its resting contact, armature 33 and its working contact, off normal springs 51 and the winding of the release magnet to battery. By the energization of the release magnet 18 the selector F is restored to normal in the usual manner 75 and the connection of the first calling subscriber with the trunk line X is broken. At the same time that the circuit of the release magnet is closed the circuit of the wiper switching relay 17 is opened and the wipers 21 and 23 are disconnected to prevent interference with other lines while the selector is returning to normal. When the connection is broken the calling subscriber will know that he can no longer use the trunk line to the branch exchange and he will replace his receiver, whereupon the remaining switches will be released. In case he has not finished his business with the subscriber at the branch exchange he may again call 80 the subscriber after waiting a reasonable length of time and in case an idle trunk line is found the connection may be reestablished as before; or in case none of the trunk lines are actually free but one or more are being held beyond the time limit, the calling subscriber will himself be in the position of the second calling subscriber previously referred to and will be able to take one of the trunk lines for his own use and release the connection of the subscriber who at that time is 85 connected therewith.

Having fully described and ascertained the features and aspects of my invention, what I consider to be new and desire to have protected by Letters Patent will be pointed out in the appended claims:

What I claim as my invention is:

1. In a telephone system, a trunk line, means including automatic switches whereby calling subscribers may extend connections over said trunk line, each connection being of unlimited duration unless another subscriber desires to use the trunk line, and means for limiting the time during which any one subscriber may hold said trunk line exclusively for his own use so as to permit another subscriber to appropriate it for use at the end of a pre-determined time.

2. In a telephone system, a trunk line, means including automatic switches whereby calling subscribers may extend connections over said trunk line, means reserving the trunk line to the exclusive use of the calling subscriber when a connection therewith has been established, and means for

- rendering the continued use of said trunk line non-exclusive after a predetermined time.
3. In a telephone system, a trunk line, means including automatic switches whereby calling subscribers may extend connections over said trunk line, means reserving the trunk line to the exclusive use of the calling subscriber when a connection therewith has been established, means for rendering the continued use of said trunk line non-exclusive after a predetermined time, and means for terminating the use of said trunk line by the subscriber first calling when it is taken for use by a second calling subscriber.
4. In a telephone system, a trunk line, means including automatic switches whereby calling subscribers may extend connections over said trunk line, means reserving the trunk line to the exclusive use of the calling subscriber when a connection therewith has been established, means for rendering the continued use of said trunk line non-exclusive after a predetermined time, and means notifying the calling subscriber when the period of exclusive use is over.
5. In a telephone system, a line, means including automatic switches whereby calling subscribers may connect with said line, means for making said line busy when connection thereto is established, said busying means being effective to prevent any other connection from being extended to said line, and means for automatically terminating the busy condition thereafter without releasing the connection.
6. In a telephone system, a line, means including automatic switches whereby calling subscribers may connect with said line, means for making said line busy when connection thereto is established, means for automatically terminating the busy condition thereafter without releasing the connection, and means for releasing the connection when a second connection to said line is completed.
7. In a telephone system, a line, means including automatic switches whereby calling subscribers may connect with said line, means for making said line busy when connection thereto is established, means for automatically terminating the busy condition thereafter without releasing the connection, and means for transmitting an audible signal to the calling subscriber to warn him that the connection is liable to be broken.
8. In a telephone system, a trunk line, a plurality of automatic switches having access to said trunk line, means for making said trunk line busy when the same is seized by one of said switches, and means operated automatically after a predetermined time to render said trunk line non-busy prior to the disconnection of said switch.
9. In a telephone system, a trunk line, a plurality of automatic switches having access to said trunk line, means for making said trunk line busy when the same is seized by one of said switches, means for rendering said trunk line non-busy after a predetermined time whereby it is again made accessible to the other switches, and means for releasing the switch first operated when the trunk line is seized by another of said switches.
10. In a telephone system, two exchanges, interconnecting trunk lines, automatic switches for use by calling subscribers in one exchange for extending connections over said trunk lines to the other exchange, busy circuit connections for rendering any trunk line inaccessible to other calling subscribers when it is taken for use, and means for altering said busy connections thereafter whereby the said trunk line is again rendered accessible to other calling subscribers without breaking the connection first established.
11. In a telephone system, a trunk line, means including automatic switches whereby calling subscribers may extend connections over said trunk line, means for reserving the trunk line to the exclusive use of the calling subscriber when a connection therewith has been established, and means operable after a predetermined time for making said line accessible to other of said calling subscribers while said line is in use.
12. In a telephone system, a trunk line, means including automatic switches whereby calling subscribers may extend connections thereover, means for maintaining an extended connection exclusively for a predetermined period and means for thereafter maintaining the extended connection subject to release by other of said calling subscribers.
13. In a telephone system, a line, means including automatic switches whereby calling subscribers may connect with said line, means for making said line busy when a connection has been established thereover, and time controlled means for automatically terminating the busy condition thereafter while the connection is maintained.
14. In a telephone system, a line, means including automatic switches whereby calling subscribers may connect with said line, means for applying a busy potential to said line when connection thereto is established, and means for automatically switching the busy potential to a nonbusy potential without releasing the connection.

Signed by me at Chicago, Cook County, State of Illinois, this 28th day of November, 1919.

BERNARD D. WILLIS.
